(57) **CLAIM**

The ornamental design for a communications base station, as shown and described.

DESCRIPTION

FIG. 1 is a front isometric view of an embodiment of a communications base station showing our new design.

FIG. 2 is a front elevation view thereof.

FIG. 3 is a back elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is an isometric view of an embodiment of a communications base station cover showing our new design.

FIG. 9 is a front elevation view thereof.

FIG. 10 is a back elevation view thereof.

FIG. 11 is a left side elevation view thereof.

FIG. 12 is a right side elevation view thereof.

FIG. 13 is a top plan view thereof.

FIG. 14 is a bottom plan view thereof.

FIG. 15 is a front isometric view of another embodiment of a communications base station cover showing our new design.

FIG. 16 is a front elevation view thereof.

FIG. 17 is a back elevation view thereof.

FIG. 18 is a left side elevation view thereof.

FIG. 19 is a right side elevation view thereof.

FIG. 20 is a top plan view thereof; and,

FIG. 21 is a bottom plan view thereof.

Any broken lines in the Figures are for illustrative purposes only and form no part of the claimed design.
